US0D1024570S

(12) **United States Design Patent** (10) **Patent No.:** **US D1,024,570 S**
(45) **Date of Patent:** **** Apr. 30, 2024**

(54) **CLEANING BRUSH**

(71) Applicant: **Zhongshan Kamshing Home Electrical Appliance Co., Ltd.**
Zhongshan (CN)

(72) Inventor: **Minshi Liang**, Zhongshan (CN)

(***) Term: **15 Years**

(21) Appl. No.: **29/853,056**

(22) Filed: **Sep. 13, 2022**

(51) LOC (14) Cl. **04-01**

(52) U.S. Cl.

USPC **D4/102; D32/19**

(57) **CLAIM**

The ornamental design for a cleaning brush, as shown and described.

DESCRIPTION

FIG. 1 is a perspective view of a cleaning brush showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the cleaning brush, shown in an closed configuration.

The dash-dash broken lines in the drawings depict portions of the cleaning brush that form no part of the claimed design.

1 Claim, 9 Drawing Sheets
